UNITED STATES PATENT OFFICE

2,430,142

CARRIER HANDLE

Stephen C. Roberts, Portland, Oreg.

Application November 30, 1945, Serial No. 631,840

1 Claim. (Cl. 224—45)

1

This invention relates to improvements in detachable handles for shopping bags, packages and also for articles of flat formation such as panes of glass, boards and the like. One of the principal objects of the invention is the provision of an article of this character which is of simple, efficient, durable and inexpensive construction and which may be adjustable to various lengths for accommodating various articles to be carried.

These and other objects will appear as my invention is more fully hereinafter described in the following specification, illustrated in the accompanying drawing, and finally pointed out in the appended claim.

In the drawing:

Figure 1 is a perspective view of a handle made in accordance with my invention.

Figure 2 is a perspective view of a modified form of the invention.

Figure 3 is a sectional view taken on the line 3—3 of Figure 4.

Figure 4 is an enlarged fragmentary view of means for adjusting the length of the legs of the handle.

Figure 5 is a sectional view taken along the line 5—5 of Figure 6.

Figure 6 is a modified form of leg-adjusting means.

Referring now more particularly to the drawing:

In Figure 1 reference numeral 1 indicates a hand grip bored as at 2 throughout its length. The main body of the handle or bail is made of two pieces of material such as wire or the like turned back on itself as at 3 and 4 to form a carrying space 5 to receive articles of flat formation such as panes of glass, boards and the like. The leg portions 6 of the handle are turned inwardly at their upper ends at substantially right angles as at 7 for insertion into the bore 2 of the hand grip. Normally the ends of the inwardly turned portions abut each other and must be sprung apart for insertion into the hand grip to prevent accidental removal.

2

For rendering the legs 6 adjustable lengthwise, I divide them into two parts 9 and 10 and the ends of these parts are inserted into a tube 11 provided with set screws 12 for locking the portions 9 and 10 in any adjustable position within the tube.

In the modified form of adjusting means shown in Figure 6 the portions 9A and 10A are held in any adjusted position in relation to each other by means of a clamp consisting of two parts 13 and 14 locked together by bolts 15 formed with winged head 16 and a nut 17.

While I have shown a particular form of embodiment of my invention, I am aware that many minor changes therein will readily suggest themselves to others skilled in the art without departing from the spirit and scope of the invention. Having thus described my invention, what I claim as new and desire to protect by Letters Patent is:

20 A carrier handle consisting of bail member having inwardly turned portions at its uppermost end and removably engaged with a handle, the opposite end of the bail member being turned back on itself for a portion of its length, each leg 25 portion of said bail member being made of two aligned parts adjustably and lockably attached to each other.

STEPHEN C. ROBERTS.
